Application March 18, 1954, Serial No. 417,090

9 Claims. (Cl. 118—11)

The present invention relates to powdering cabinets used by photoengravers in powdering partially etched plates before further etching and has specific reference to such a cabinet having means to prevent powder escaping from the cabinet to atmosphere during the powdering operation.

Objects and advantages of the invention will be set forth in part hereinafter and in part will be obvious herefrom, or may be learned by practice with the invention, the same being realized and attained by means of the instrumentalities and combinations pointed out in the appended claims.

The invention consists in the novel parts, constructions, arrangements, combinations and improvements herein shown and described.

The accompanying drawings, referred to herein and constituting a part hereof, illustrate one embodiment of the invention, and together with the description, serve to explain the principles of the invention.

In the drawings:

Figure 1 is a perspective view of the powder cabinet embodying the present invention and being partially broken away to show the mechanism within the interior of the cabinet;

Figure 2 is a vertical sectional view of the cabinet taken generally along line 2—2 of Figure 3;

Figure 3 is a transverse sectional view taken along line 3—3 of Figure 2; and

Figure 4 is a diagrammatic view of the electrical circuit which forms as part of the present invention.

In preparing partially etched plates for further etching a dark red resin, known as dragons blood, is dusted onto the plates. In dusting the plate, a flat brush charged with the powder is swept across the plate in four different directions varying approximately 90° with the plate being heated after it has been dusted in each direction, this heating melting the powder so it becomes fused and forms an acid resistant coating. By dusting in this manner, the powder is effectively applied to the partially etched image so that when the plate is treated with acid for further etching the relief will be increased without undercutting or losing the detail.

During the dusting or powdering operation the fine powder is agitated so that particles of the powder rise into the air in the fashion of dust. For the safety of personnel as well as other reasons it is essential that this powder does not escape and become lost to the atmosphere. It is for this reason that the powdering operation is conducted in specially-designed cabinets.

The present invention has for its objects the provision of an improved cabinet for use in powdering partially etched plates and wherein the powder that rises from the plate during the powdering operation is recovered by means of a downdraft air flow system without disturbing the quiescent atmosphere in the vicinity of the plate or in any way interfering with the powdering of the plate. Another object is an improved powder cabinet having a recovery system for the powder rising from the plate

2

during the powdering operation with the recovery system being automatically kept at a high operating efficiency through normal operation of the cabinet. A further object is the provision of a powder cabinet which is relatively simple yet highly efficient and which gives the operator maximum working freedom.

In accordance with the illustrative and preferred embodiment of the invention the powder cabinet comprises a base on the upper end of which is a box-like hood 10 provided with spaced vertical side walls interconnected by spaced vertical front and rear walls. The top of the hood is entirely open and the front wall is considerably lower than the rear wall with the upper edges of the side walls preferably sloping gradually downward from the top of the rear wall to the top of the front wall. Positioned within the hood is a powder tray of generally the same configuration as the hood but smaller in all respects so that it is contained entirely within the hood with the upper edges of the walls of the tray being below the corresponding edges of the hood and with the walls and bottom of the tray being spaced from the walls and bottom of the hood thereby providing a narrow passage for air flow all the way around the tray. The interior of the hood and the interior of the base are separated 25 by a plate which forms the bottom of the hood and which is provided with a pair of openings each of which has an upright fabric filter bag positioned therewithin and depending into the base of the cabinet. Within the base is a fan driven by an electric motor and adapted to apply a suction to the interior of the base causing a flow of air downward through the passage surrounding the powder tray, into the open upper end of the filter bag, and through the wall of the bag into the interior of the base from which it is exhausted by the fan to atmosphere. 30 In flowing through the wall of the filter bag the powder that is entrained in the air is removed and remains in the interior of the bag. Attached to these filter bags is an electric vibrator operative when energized to shake the bags to remove the powder that clings to the inner wall of the bags, this powder falling into the bottom of the bag leaving the walls relatively clean for efficient filtering operation. Energization of the electric motor and the vibrator is controlled through suitable electric circuits which include a switch means operable when 35 in one position to energize the motor and de-energize the vibrator and when in another position to de-energize the motor and energize the vibrator. In the circuit associated with the vibrator is a switch automatically operative to de-energize the vibrator a predetermined time after it has been energized.

Referring now to the drawings, wherein like reference characters are used throughout to designate like elements, the illustrative and preferred embodiment of the powder cabinet of the present invention shown therein comprises base 10 provided with side walls 14, rear wall 16 and bottom member 18. The inner portion of the front 20 of this base is recessed as shown and provided at its upper end with a receptacle for drawer 21 beneath which is access opening 22 normally closed in a fluid tight manner by removable plate 24. The front wall 20 and side walls 14 of base 10 extend below bottom member 18 and provide a footing for the base in engagement with the floor upon which the cabinet is placed with passage 23 being formed between the bottom member and the floor and leading out the back of the cabinet.

Upon the upper end of base 10 is formed the hood portion of the cabinet, this hood portion being generally designated 12 and including bottom plate 25 preferably positioned on top of base 10 and forming what may be termed the roof of the base with the front end of the plate being bent upwardly to form the front wall 26 of the hood. The side and rear walls of the hood are

formed by upward extensions of side walls 14 and rear wall 16 of base 10 with the rear wall 16 of the hood being substantially higher than front wall 26 as shown and with the upper edges of side walls 14 sloping gradually downward from the top of the rear wall to the top of the front wall thereby giving the operator a maximum of working freedom which promotes both production and quality.

Mounted within hood 12 is powder tray 27 having side walls 28, rear and front walls 30 and 32, respectively, and bottom 34. The tray is pivotally mounted about rod 36 which extends through a suitable bead formed at the upper edge of rear wall 30 and has its opposite ends secured to side walls 14 of the hood. When the powder tray is in its normal or operative position, shown in full lines in Figure 1 and dotted lines in Figure 2, the bead or loop provided on the upper edge of front wall 32 is in engagement with stop member 38 secured to side wall 14 of the hood and bottom 34 is in parallel relation with but spaced from bottom plate 25 of the hood forming passage 40 therebetween. The side walls 28 and front and rear walls 32 and 30 of the tray are respectively spaced from side walls 14 and front and rear walls 26 and 16 of the hood thereby forming annular passage 42 about the tray and communicating at its lower end with passage 40.

For the purpose of somewhat guiding tray 27 in its pivotal movement about rod 36 and for retaining the tray in its extreme upwardly tilted position bracket 44 has one end pivotally mounted to the bottom of the tray with its other end pivoted to member 46 which is in turn slidably mounted on track 48. As tray 27 is tilted upward member 46 slides along track 48 until bracket 44 is substantially vertical whereupon the bracket will hold the tray in this position. By tilting the tray in this manner the powder in the tray collects at the back of the tray making it relatively easy to remove the powder with this removal being facilitated by plate 50 which extends across the lower rear edge of the tray.

Pivoted on the upper edge of front wall 26 of the hood is shelf 60 which is movable between its full line position in Figure 2 where it permits pivotal movement of tray 27 and its full line position in Figure 1 where it extends over and is spaced from the upper edge of the front wall of the tray and prevents foreign matter falling in the space between the front walls of the tray and the hood.

In bottom plate 24 is a pair of openings 52 within each of which is an upright close mesh fabric filter bag 54 preferably made of nylon and which extends downwardly into the interior of base 10. The rim of bag 54 is formed with a rigid annular member 56 disposed therein with this rim being slightly larger than opening 52 thereby forming a radial flange effective to support the bag. To prevent the bags from collapsing and becoming out of shape each of them has a hoop 58 positioned in the bottom.

During the powdering of a plate within tray 27, such as plate 62 held by hand or placed on shelf 60, a continuous downdraft is created in annular passage 42 by fan 64 mounted within base 10 and having its inlet communicating with the interior of the base and its outlet communicating with passage 23. The base 10 is sufficiently air tight so that fan 64 produces a partial vacuum in the interior of the base causing air to flow downwardly through passage 42, through passage 40 into filter bags 54, through the walls of the bags into the interior of the base and then through the fan to passage 23 which directs it out the back of the cabinet to atmosphere. During the powdering operation the air entering the filter bags is laden with powder, but in passing through the walls of the bags this powder remains on the inside with this filtering operation being so efficient that the air may then be exhausted to the room and need not be conveyed to a remote point of disposal.

By creating a downdraft through annular passage 42 the entire tray is surrounded by a current of air moving toward the passage 42 with the air over tray 27 moving generally outwardly from the center toward each of the walls whereby no rush of air above or across the tray from one end to the other is created as has been the case heretofore and whereby the quiescent atmosphere necessary for quality work is undisturbed while dust collection efficiency is greatly improved.

In order to maintain the efficiency of filter bags 54 at their maximum a shaker is provided to periodically shake the bags to remove the powder that clings to the interior wall of the bags, with this powder falling to and collecting in the bottom of the bag. The bags are of sufficient size so that under normal operation they need emptying only about twice a year with the emptying operation being accomplished by tilting tray 27 to its uppermost position and then removing the bags upwardly out of the openings 52.

As illustratively disclosed the means for shaking bags 54 comprises electromagnet 66 having its armature 67 normally biased to a non-energized position by spring 68 and connected with the bags by cross bracket 70 pinned to the radially extending ears 72 which form part of annular frame 74 secured to each of the bags. Extending laterally from armature 67 is bracket 76 which has a pair of fingers 78 between which is positioned switch 80 forming a part of the circuit of electromagnet 66 and arranged to open and break the circuit when armature 67 is moved to its extreme position within the coil of the electromagnet in response to energization of the electromagnet and to close when armature 67 is moved to its other extreme position by spring 68 with the limit of these two extreme positions being determined by stops 82 which engage bracket 76. Thus when the circuit of electromagnet 66 is energized armature 67 will rapidly move back and forth between these extreme positions because of the opening and closing of switch 80 thereby resulting in shaking filter bags 54.

The operation of fan 64 and electromagnet 66 is controlled by an electric circuit diagrammatically illustrated in Figure 4 and arranged so that when the motor 84 of the fan is energized electromagnet 66 will not be energized and can only be energized after motor 84 has first been energized and then de-energized. Electromagnet 66 will be energized only for a predetermined time after which it will automatically be de-energized. This circuit comprises a pair of leads 86 and 88 connected with a suitable source of potential and across which are connected motor 84 and coil of relay 90 in parallel relation with each other with the circuit of motor 84 including conductors 92 and 94 and the circuit of relay 90 including conductors 96 and 98. Forming a portion of the conductors 92 and 96 is switch 100 which is preferably a double pole, double throw switch of the toggle type without an off position. When switch 100 is moved to the right, as viewed in Figure 4, into engagement with contacts 102 and 104, conductors 92 and 96, respectively, are completed while when it is moved to its left in engagement with contact 106 both of these conductors are broken and contact 106 is connected to relay 90 through a portion of conductor 96.

Thus when switch 100 is moved to its right position motor 84 and relay 90 are energized. Energization of relay 90 causes normally open contacts 108 and 110 of the relay to close and establishes through conductor 112 a holding circuit for the relay in parallel with switch 100 so that when the switch is moved to its left position relay 90 will remain energized while motor 84 will become de-energized.

The circuit for electromagnet 66 includes contact 106, conductor 114, a series connected switch 80 and conductor 116 which is connected to lead 88. When switch 100 is moved from its right to its left position in engagement with contact 106 this circuit of electromagnet 66

is completed across leads 86 and 88 since contact 106 is then connected with lead 86 through conductors 96 and 112 and contacts 108 and 110. However, should relay 90 become de-energized causing contacts 108 and 110 to open the circuit of electromagnet 66 would of course become de-energized.

In series with coil of relay 90 and forming a part of conductor 98 is thermal switch 118 which comprises bimetal element 120 in engagement with contact 122 at normal temperature and movable out of engagement with the contact when its temperature is raised to a predetermined value. Immediately adjacent to bimetal element 120 is resistance heater 124 connected across conductors 114 and 98. No current can flow in resistance 124 until contacts 108 and 110 of self-locking relay 90 are closed which is accomplished by throwing the switch 100 to the right. Resistance 124 then is in a position to receive current when switch 100 is thrown to the left hand position making contact 106 which completes the path to resistance 124 namely conductor 88, thermal switch arm 120, contact 122, conductor 98 to heater, conductor 114, contact 106, switch 100, conductor 96, conductor 112 and contacts 108 and 110 to conductor 86. When switch 100 is thrown left connecting to contact 106 the circuit of electromagnet 66 is energized, current will flow from conductor 114 through the resistance heater to conductor 98 causing the resistance heater to become hot and thereby heat bimetal element 120 resulting in switch 118 being opened which will in turn de-energize electromagnet 90, opening contacts 108 and 110, with resulting de-energization of the circuit of electromagnet 66.

Since switch 100 is preferably of the toggle type it will at all times occupy either its right position in engagement with contacts 102 and 104 or its left position in engagement with contact 106.

In operating the cabinet of this invention, when it is desired to powder a partially etched plate switch 100 is first moved to the right completing the circuit of motor 84 thereby causing fan 64 to draw air downward through passage 42 and also completing the circuit of relay 90. Energizing of relay 90 causes contacts 108 and 110 to close thereby completing the holding circuit of the relay which is in parallel with switch 100. After the powdering operation is completed and it is no longer necessary to run fan 64, switch 100 is moved to the left into engagement with contact 106. This movement of switch 100 de-energizes motor 84 but because of the holding circuit does not de-energize relay 90. Upon moving the switch into engagement with contact 106 the circuit of electromagnet 66 is completed resulting in shaking of the filter bags 54. Also incident to energization of the circuit of electromagnet 66 resistance heater 124 begins to get hot and after a predetermined time, depending upon the resistance value of the heater, it will have heated bimetal element 120 sufficiently to cause it to move away from contact 122 which will de-energize relay 90 and consequently cause de-energization of the circuit of electromagnet 66. Thus filter bags 54 will be shaken only for a short time sufficient to remove the powder from the inner walls thereof after which the electric vibrator will be automatically de-energized.

The invention in its broader aspects is not limited to the specific mechanisms shown and described but departures may be made therefrom within the scope of the accompanying claims without departing from the principles of the invention and without sacrificing its chief advantages.

What is claimed is:

1. A powder cabinet of the type described comprising a hood forming the upper portion, said hood having an open top and a front the major portion of which is open, a powder tray having side, rear and front walls and providing a normally horizontal working surface disposed within said hood, said tray being smaller than said hood

so that passages are formed between the side, rear and front walls of the tray and the hood and the tray is positioned entirely within the hood, means in the lower portion of said cabinet effective to draw air downwardly through said passages, and separator means through which said air is directed for separating foreign matter therefrom.

2. A powder cabinet for use in preparing plates for etching comprising a generally upright base, a hood mounted on said base and forming the upper portion of the cabinet, said hood being open on the top and having elements comprising a bottom and generally upright walls enclosing the front, rear and sides thereof with the front wall being substantially lower than the rear wall and with the edges of the side walls sloping from the rear wall downward to the front wall, a powder tray providing a normally horizontal working surface and being of generally the same configuration as said hood and disposed entirely within said hood, the bottom and walls of said tray being spaced from the corresponding elements of said hood thereby forming a narrow passage for airflow entirely surrounding said tray, said tray being pivotally mounted adjacent the rear wall of said hood about an axis extending along the upper edge of the rear wall of said tray the bottom of said hood having an opening therein, a fan disposed in the base of the cabinet and effective to apply a suction to said passage through said opening causing a downward flow of air through said passage on all sides of the tray, and an upright close mesh fabric filter bag removably disposed within said opening for removing foreign matter from the air drawn through said opening.

3. A powder cabinet as defined in claim 2 including a shelf hingedly mounted on the upper edge of the front wall of the hood and positionable so as to extend toward the rear of said hood beyond and above the front wall of the powder tray.

4. A powder cabinet of the type described comprising a base, a hood positioned on the upper end of said base, said hood having a generally horizontal bottom member, a pair of spaced side walls extending upwardly from said bottom member, a front and a rear wall extending upwardly from said bottom member intermediate between and interconnecting said side walls, said front wall being substantially lower than said rear wall and the upper edges of said side walls sloping gradually downward from the top of the rear wall to the top of the front wall, a powder tray having a bottom and side, rear and front walls disposed within said hood, the bottom of said tray providing a working surface and being spaced above the bottom member of the hood and the walls of the tray being spaced from the walls of the hood thereby forming a narrow passage completely around said tray, the upper edges of the walls of the tray being positioned below the corresponding edges of the walls of the hood, said tray being pivotally mounted with respect to the rear wall of said hood and about an axis at the upper edge of the rear wall of said tray the bottom member of the hood having an opening therein, an upright filter bag disposed within said opening, substantially filling the same and depending into the base of the cabinet, and a fan in the base of said cabinet effective to draw air downwardly through the passage around said tray and into said bag and through the wall thereof.

5. A powder cabinet comprising an upright base, a hood having side, rear and front walls and mounted on said base and forming the upper portion of said cabinet, said hood being adapted to have a powder tray providing a working surface disposed therein with the peripheral extremities of said tray spaced from said hood walls to provide a passage for air flow surrounding said tray, a fan in the base of said cabinet effective to draw powder laden air through said hood into said base, an upright

close mesh fabric filter bag disposed in the path of said powder laden air being drawn into said base so that the air enters the open upper end of the bag and passes through the wall of the bag, an electric motor connected to said fan, switch means movable between a first and a second position and being constructed and arranged to occupy one of said positions at all times, said switch means having a pair of contacts forming a part of the circuit of said motor said contacts being closed when the switch means is in one of said positions and open when in the other of said positions, an electric vibrator connected to said bag and operative to vibrate the same when energized, said switch means having a pair of contacts forming a part of the circuit of said vibrator, the last named contacts being closed when the switch means is in said other position and open when in said one position, and means operative a predetermined time after energization of said vibrator to de-energize the same.

6. A powder cabinet comprising a base, a hood mounted on said base and having front, rear and side walls, a powder tray providing a working surface disposed within said hood and having its peripheral extremities spaced from said hood walls to form an air flow passage surrounding said tray, an upright filter bag in said cabinet, a fan operative to draw powder laden air through said hood air flow passage, into the open upper end of the filter bag and through the wall of the bag, means for driving said fan including an electric motor disposed in an electric circuit adapted to be connected across a potential, an electric switch means in said circuit and movable between a first and a second position to cause energization and de-energization respectively of said circuit, said switch means being constructed and arranged to at all times occupy one of said positions, a second circuit in parallel with the first mentioned circuit and including an electric vibrator operatively connected to said filter bag, said switch means including means effective to make and break said second circuit when said switch means occupies its second and first positions respectively, additional means in said second circuit effective to control energization thereof, said means being conditioned in response to said switch means occupying its said first position to permit energization of said second circuit, means operable to maintain said control means so conditioned when said switch means is moved from its first to its second position, and means effectively responsive to energization of said second circuit and operable after said second circuit has been energized for a predetermined time to condition said control means to prevent energization of said second circuit.

7. A powder cabinet comprising a base, a hood mounted on said base and having front, rear and side walls, a powder tray providing a working surface disposed within said hood and having its peripheral extremities spaced from said hood walls to form an air flow passage surrounding said tray, a close mesh filter bag in said cabinet, a fan operative to draw powder laden air through said passage, into the open end of the filter bag and through the wall of the bag, an electric circuit including a motor connected to drive said fan, switch means having a pair of contacts in said circuit, said switch means being movable between a first and second position to respectively close and open said contacts, a second circuit in parallel with said motor and including a pair of contacts forming a part of said switch means, said contacts being in engagement when the switch means is in said first position and separated when in said second position, a relay having its coil in series with said second circuit, the contacts of said relay being normally open and being connected to form a holding circuit for the relay in parallel with said contacts in said second circuit, a normally closed thermal switch in series with said second circuit and said holding circuit, said switch moving to an open position

upon reaching a predetermined high temperature, a magnetic vibrator operatively connected to said filter bag, said vibrator being in series with said holding circuit and parallel with said relay coil and said thermal switch, said switch means including means operative to open the vibrator circuit when said switch means is in said first position and complete said vibrator circuit when said switch means is in said second position, an electric resistance heater juxtaposed to said thermal switch and connected in series with the last mentioned means and said thermal switch.

8. A powder cabinet used in preparing plates for etching comprising a base, a hood disposed on the upper end of said base, said hood having an open top, and generally vertical walls with the front wall being substantially lower than the rear wall, the interior of said hood being separated from the interior of said base by a plate member having an opening therethrough, a powder tray providing a working surface disposed within said hood, said tray having a bottom and generally vertical walls spaced from the walls of the hood with the upper edges of its walls disposed well within the corresponding edges of the walls of the hood, the bottom of the tray being spaced above said plate member, a fan in said base for applying a suction to the space between the walls of the tray and the walls of the hood through said opening in the plate member thereby causing a downward flow of air through said space, a close mesh filter bag filling said opening and depending into said base, an electric circuit including a motor for driving said fan, an electric circuit including a vibrator connected to said bag and effective to vibrate the same when energized, switch means disposed in the circuit of said motor and the circuit of said vibrator and movable between a first and a second position wherein it is effective to respectively make and break the circuit of the motor and break and make the circuit of the vibrator, and means responsive to energization of said vibrator circuit and operable to break said vibrator circuit after energization of the same for a predetermined time.

9. A powder cabinet having a hood forming the upper portion thereof, said hood having side and rear walls, an open top and a front the major portion of which is open, a powder tray having side, rear and front walls and substantially centrally disposed within said hood, said tray providing a working surface and being generally of the same configuration as said hood but smaller in all respects so as to form an annular passage about said tray between the walls of the tray and the hood and so the tray is positioned entirely within the hood, a fan in the lower position of the cabinet operative to apply a suction to the lower end of said passage and draw powder laden air downwardly therethrough, an upright fabric filter bag disposed in the path of said powder laden air, means for driving said fan including an electric circuit adapted to be connected across a potential, an electric switch means in said circuit and movable between a first and a second position to cause energization and de-energization respectively of said circuit, said switch means being constructed and arranged to at all times occupy one of said positions, a second circuit in parallel with the first mentioned circuit and including an electric vibrator operatively connected to said filter bag, said switch means including means effective to make and break said second circuit when said switch means occupies its second and first positions respectively, additional means in said second circuit effective to control energization thereof, said means being conditioned in response to said switch means occupying its said first position to permit energization of said second circuit, means operable to maintain said control means so conditioned when said switch means is moved from its first to its second position, and means effectively responsive to energization of said second circuit and operable after

said second circuit has been energized for a predetermined time to condition said control means to prevent energization of said second circuit.
